Patented Oct. 4, 1921.

FIG - 2 -

INVENTOR
Edwin P. Shannon,
By Burnham & Crampton,
His atty.

UNITED STATES PATENT OFFICE.

EDWIN P. SHANNON, OF LOCKLAND, OHIO.

CLAMPING MEANS FOR ROTARY MEMBERS.

1,392,363.

Specification of Letters Patent.

Patented Oct. 4, 1921.

Application filed January 24, 1920. Serial No. 353,774.

To all whom it may concern:

Be it known that I, EDWIN P. SHANNON, a citizen of the United States, and a resident of Lockland, in the county of Hamilton and State of Ohio, have invented a certain new and useful Clamping Means for Rotary Members; and I do hereby declare the following to be a full, clear, and exact description of the invention, such as will 5 enable others skilled in the art to which it appertains to make and use the same, reference being had to the accompanying drawings, and to the characters of reference marked thereon, which form a part of this 10 specification.

This invention relates particularly to means for clamping rotary members, such for instance, as grinding or polishing wheels, rotary saw and slitter blades, and the like; 15 and has for its primary object the provision of a clamping means of this character which has its members relatively turnable on a carrying shaft or means to effect a tool clamping or releasing action of the clamping 20 members, the turning of the members or either of them, to effect a gripping of a tool, being accomplished by a movement thereof 25 reverse to the intended direction of driving of the shaft, the resistance offered to a turning 30 of the tool by the work being acted on tending to effect a firmer clamping of the clamping members on the tool.

Further objects and advantages of the invention will be apparent from the following 35 detailed description thereof.

While the invention in its broader aspect is capable of embodiment in numerous forms, a preferred embodiment thereof is illustrated in the accompanying drawings, 40 in which,—

Figure 1 is a side elevation of an apparatus embodying the invention in work-clamping relation on a shaft and with a portion in central section longitudinally of 45 the shaft. Fig. 2 is an end elevation thereof with the shaft in section and with a portion of the clamping member broken away, and Fig. 3 is a section on the line 3—3 in Fig. 1.

Referring to the drawings, 1 designates a 50 shaft, and 2 and 3 a pair of work clamping members mounted for rotary and axial movements on the shaft and adapted to clamp a tool 4 between their adjacent ends.

The hub or sleeve portions of the clamping 55 members are provided internally with spiral

grooves or threads 5, with the groove or thread of one reverse to that of the other, or one forming a right and the other a left hand thread. The shaft is provided within 60 each clamping member with one or more pins or studs 6 projecting into the thread of the respective member so that a turning of the members relative to the shaft will impart movements to the members longitudinally 65 of the shaft. It is evident that by reversing the forms of the threads on the two clamping members, the members when turned in one direction relative to the shaft will be caused to have a receding or operating 70 movement, and when turned in the opposite direction relative to the shaft will be caused to have a clamping movement toward each other.

The direction of tool clamping rotation of 75 the clamping members should be opposed to the normal direction of driving of the shaft 1, so that any resistance which is offered to a turning of the tool 4 and engaged clamping members by the coaction of work with 80 the tool will tend to effect a tightening of the clamping members on the tool rather than a loosening movement thereof relative to the shaft.

One or both of the clamping members may 85 be provided with a set screw 7 for locking the member in adjusted position to the shaft, and in practice it is preferable to provide one of the clamping members with an adjusting screw 8, which is threaded through 90 its hub or sleeve portion in tangential relation to a circle concentric to the hub axis and adapted to have thrust engagement at its inner end with a shoulder 9 formed by one side of a recess provided in the shaft 1, 95 whereby an inward turning of the screw will effect a tightening of the clamping member with respect to its companion.

The clamping members 2 and 3 may be secured in clamping relation to a tool 4 by 100 a pin 10 inserted through registering openings in the coacting inner flanged ends of the clamping members. A proper registering of the pin receiving openings in the clamping members to receive the pin when the 105 members are in proper tool clamping position, may be obtained by tightening the members to the extent desired against a tool being held thereby and then drilling a hole through the flange portions of the two members and inserting the pin 10 therein.

If a worn or broken tool 4 is replaced by

another of the same size and style, the pin receiving holes in the two members will ordinarily be brought into register when the members are in proper clamping relation to the tool. In releasing the clamping members from the tool it is only necessary to turn one clamping member on the shaft relative to the other clamping member so that the clamping position of the other, or stationary member, need not be disturbed.

It is evident that I have provided a simple and efficient clamping means for use in connection with shafts to hold a tool in engagement therewith and that it may be easily operated to effect a clamping or releasing of the tool.

The tool 4 if desired, may be provided with dowel pins 11 for seating in sockets in one or the other of the members, this arrangement being particularly desirable when a sectional tool is provided, the dowel pins then serving to retain the sections in assembled relation and resisting an outward throwing of the same when being rotated at high speed.

I wish it understood that my invention is not limited to any specific construction, arrangement or form of the parts, as it is capable of numerous modifications and changes without departing from the spirit of the claims.

Having thus described my invention, what

I claim as new and desire to secure by Letters Patent, is,—

1. In combination, a shaft, a pair of 35 collars mounted on the shaft and having their adjacent ends adapted for clamping a tool therebetween, each collar having its bore of a size for rotatably fitting the shaft and provided with an internal thread with 40 the thread of one collar reverse to that of the other, means fixed to the shaft and entering the threads of the respective collars to cause the collars to have axial opposed movements when rotated in the same direction on the 45 shaft, and means for locking the collars in adjusted relation to the shaft.

2. In combination, a shaft, a pair of 50 collars fitted for turning movements on the shaft, and having their adjacent ends adapted to grip a tool therebetween, each collar having an internal thread with the thread of one collar reverse to that of the other, a pin fixedly projecting from the shaft with 55 in each collar and entering a thread thereof whereby opposed axial movements are imparted to the collars when turned in the same direction relative to the shaft, and means for locking the shaft in adjusted relation.

In testimony whereof I have hereunto signed my name to this specification.

EDWIN P. SHANNON.
